UNITED STATES PATENT OFFICE.

WILLIAM CERIL OURSLER, OF MEMPHIS, TENNESSEE, ASSIGNOR TO SAM RICE
OURSLER, OF MEMPHIS, TENNESSEE.

AUTOMATIC CLEANING DEVICE FOR SPARK-PLUGS.

1,343,743.

Specification of Letters Patent. Patented June 15, 1920.

Application filed October 10, 1919. Serial No. 329,761.

To all whom it may concern:

Be it known that I, WILLIAM CERIL OURSLER, a citizen of the United States, residing at Memphis, in the county of Shelby and 5 the State of Tennessee, have invented certain new and useful Improvements in Automatic Cleaning Devices for Spark-Plugs, of which the following is a specification.

This invention relates to means for automatically keeping the porcelain portions of 10 spark plugs free from deposits of products of combustion.

The invention may be applied to different types of plugs but is shown as applied to a 15 spark plug now on the market.

The invention consists in the novel features of construction hereinafter described, pointed out in the claims, and shown in the accompanying drawings, in which:—

Figure 1 is a side elevation, partly broken away, a portion of the wall being in section, and cleaning disks being shown in normal position in full lines and in raised position in dotted lines.

25 Fig. 2 is a section on the line 2—2 of Fig. 1.

In the drawing 1 represents a spark plug as a whole having a shell 2, and porcelain portion 3, and sparking points 4. Fitting 30 loosely upon the portion 3 and slidably thereon and within the shell are flat disks 5. One, two or more of these may be employed, and I have illustrated the device as having 35 two disks. It will be noted that these disks are of such diameter that the distance between them and the shell is slightly greater than the spark gap between the points 4 and the shell 2. This is to prevent danger of 40 sparking between the disks and the shell.

Normally there is an equal pressure on 45 both faces of the disks when the compressed gases are ignited. The explosion, however,

takes place below the disks, thereby creating a greater pressure beneath the disks than exists above them. To equalize this pressure 45 the gases will push past the disks and upwardly into the shell, and the pressure being greater on the underside the disks will be lifted, but as the pressure equalizes this lifting movement will be checked, and the 50 gases passing the rings will act as a cushion, preventing danger of the disks being wedged on the upper portion of the porcelain portion 3. When the exhaust takes place the 55 operation will be reversed, the pressure falling on the under faces of the disks, and the disks will fall to normal position both by reason of gravity and downward movement of the gases. This cycle is repeated with each explosion, and it will be obvious that 60 as the rings move up and down on the portion 3 of the plug they will effectually prevent the accumulation of any deposit thereon.

What I claim is:—

1. In a spark plug having a shell, a portion of insulating material arranged within said shell, a point carried by said portion spaced from the shell, said space forming a spark gap, and a disk working loosely upon 70 said portion of insulating material, the distance between said disk and the shell being greater than the width of the spark gap, said disk being movable upwardly by gas pressure.

2. The combination with a spark plug having a shell, a porcelain portion within the shell and a spark gap at the lower end of the shell, a flat disk loosely movable upon the porcelain portion and spaced from the 80 shell, said disk being lifted upwardly by force of the explosion taking place below it.

In testimony whereof I affix my signature.
WILLIAM CERIL OURSLER.
